United States Patent Office

Des. 193,434
Patented Aug. 21, 1962

193,434

PANEL FOR AN AMUSEMENT DEVICE

David H. Braun, Miami, Fla., assignor to All-Tech Industries, Inc., Hialeah, Fla., a corporation of Florida

Filed Aug. 15, 1961, Ser. No. 66,352

Term of patent 14 years

(Cl. D34—5)

The FIGURE is a plan view of a panel for an amusement device showing my new design.

The dominant features of the design are shown in full lines.

The article is of no appreciable or substantial thickness and the features of the design are flush with the surface of the panel.

I claim:

The ornamental design for a panel for an amusement device, as shown and described.
